UNITED STATES PATENT OFFICE.

ERNST LARSSON, OF MANSFIELD, OHIO, ASSIGNOR TO THE OHIO BRASS COMPANY, OF MANSFIELD, OHIO, A CORPORATION OF NEW JERSEY.

COUPLING SUPPORT.

1,401,990.

Specification of Letters Patent. Patented Jan. 3, 1922.

Application filed February 19, 1920. Serial No. 359,894.

To all whom it may concern:

Be it known that ERNST LARSSON, a citizen of Sweden, residing at 29 Wood Street, Mansfield, in the county of Richland and 5 State of Ohio, has invented certain new and useful Improvements in Coupling Supports, of which the following is a specification.

My invention relates to those classes of devices known as spring draw bar carriers 10 for flexibly supporting the coupling device and for centering the coupling device prior to the coupling of cars, and combines these functions by proper relation of the parts and cooperation, into one structure.

15 One of the objects of my invention is for the structure, as a whole, to permit a side or lateral movement of the coupler which is advisable when two cars are coupled and move around curves.

20 Another object of my device is to maintain the coupling head in a normal or centered position with respect to the car body to which it is attached in order that two coupler heads may be automatically coupled 25 on a straight track or curve of moderate radius.

Another object of my device is to permit 30 the coupling heads to move up and down relatively to the car body when in a coupled position as is advisable when the coupled cars are passing over a break in the grade, under which condition the couplers will be moved downward relatively to the car body if the cars are passing upward 35 or downward at the upper end of the grade and move upwardly relatively to the car body if the car is passing over a break of grade at the lower end of the grade, all of which is a common condition met with, 40 especially in the operation of electric cars operating in cities and towns.

Other objects of my invention will appear hereinafter.

For the attainment of these ends, and the 45 accomplishment of other new and useful objects, as will appear herein, this invention consists in the features of novelty in the construction, combination and arrangement of the several parts generally shown in the 50 accompanying drawings and described in the specification, but more particularly pointed out in the appended claims.

In the drawing—

Fig. 1 shows an end elevation view of my

invention partly in section and the normal 55 position of the device is represented in full lines, the arrangement of the parts when two coupled cars are passing over the top of a hill is represented by the dotted lines and shows the action of the device as a 60 spring carrier.

Fig. 2 shows an end elevation view of my invention in part section and shows the arrangement of the parts when the coupled cars are rounding a curve, and the couplers swing together laterally with respect to the car body.

Fig. 3 is a side elevation view of my device as represented by the end elevation view in Fig. 1 and shows the coupler head 70 and my supporting device in normal position by the full lines and in a depressed condition when the coupled cars are passing over the top of a hill, by the dotted lines.

I will first describe the construction by 75 which my invention is carried out and as shown in the drawing and will later describe the operation of the various elements as necessary to meet the requirements of my invention.

In Fig. 1, C represents the sill of a car body usually located adjacent the end of the car.

Numeral 1 represents a supporting casting secured to the sill by means of the bolt 85 and nut 2; 3 is a housing comprising the tubular portion 4 and the projecting extension 5 which is provided with an opening through which passes the pin 6 for supporting the housing from the supporting member 1 and permitting lateral relative movement of the housing 4 and the support 1.

The support member 1 is provided with depending skirt 7 which limits lateral movement of the housing 4 in either direction. 95 Secured to the lower end of the housing is a closing member 8 and which I have shown as having a threaded engagement with the housing 4 although other means of connection can be used and which will be quite 100 obvious. Within the housing is a washer member 9 and secured thereto is a rod 10 having an eye attachment at the lower end. Interposed between the washer 9 and the member 8 is a spring 11 under compression 105 and the amount of compression upon the spring may be varied by adjusting the relative location or position of the member 8.

Secured to the lower end of the member 10 and supported thereby is a yoke member 12 provided with upright members 13. The yoke member 12 is provided with means 14 for receiving the lower end of the member 10 and the members 10 and 12 are secured together by the pin 15 which permits lateral movement of the parts; in Figs. 1 and 2 the coupler draw bar 16 is shown in section 10 in its normal position when supported by my invention.

It is usual to support the rear end of the coupler draw bar and to secure it to the car body and such construction I have shown 15 in Fig. 3 and here I have shown a sill C¹ to which is secured a supporting casting 17 secured to the sill by means of the bolt 18. The rear end of the coupler draw bar is secured to the support casting 17 by means 20 of the pin 19 and this arrangement permits of freedom of movement of the one end of the draw bar not only vertically but horizontally also as sufficient clearance is allowed between the parts for horizontal movement. 25 Sills C and C¹ are secured to the car body D.

It is well known that when two cars are coupled together by means of couplers which are practically rigid at their point of coupling and such cars are run over a break 30 as in the case of the cars mounting a hill, that when the front car passes over the hill that the couplers will be depressed relatively to the bodies of both cars. This will bring a severe strain upon the equipment if the 35 device supporting the couplers from the car body is of a rigid character, but in my device the interposing of the spring between the point of support to the car body and the point of support of the draw bar or 40 coupler head will permit of the coupler head being depressed without injury to the equipment. The supporting mechanism is usually mounted in such a way as to maintain the couplers at a uniform height above the rail 45 under normal conditions and this is indicated in Fig. 1 by the heavy lines and when the coupled cars are passing over a break in grade as described, the coupler will depress the supporting yoke 12 and consequently 50 the supporting spring 11 and the spring will then return the coupler head to its normal position after the cars have reached a normal stretch of track. The depressed position of the coupler head at time 55 of making the break in grade is indicated by the dotted lines in Fig. 1 and also in Fig. 3.

Another object of my invention is to permit lateral movement of the coupler head relatively to the car body as is required when 60 the cars are rounding a curve and this is brought about by pivoting the supporting housing 4 and member 10 to the car body and yoke 12 respectively, and such condition is shown by the relation of the parts in Fig. 65 2. Here we find the center of the coupler

head swung over to the right the distance between the lines A—A and A¹—A¹ and likewise the lower end of the member 10 and its pivotal point of attachment to the yoke 12 as swung to the right the distance between the lines B—B and B¹—B¹. This lateral movement can be arrested if desired by the engagement of the member 5 with the member 7 and the amount of lateral movement is dependent upon the relation of 75 these two parts 5 and 7.

It is also desirable to have the couplers maintain a normal position respecting the center of the car body when it is not coupled to another car in order that it will be in 80 a position to automatically couple with another car similarly equipped, thus avoiding the necessity of manually alining the couplers before they can be coupled. This condition is best brought about by having the couplers 85 when not in a coupled position maintained on the center line of the car as indicated by the line A—A.

With the device shown where it is pivoted to swing laterally, gravity of course would tend 90 to bring the coupler back to normal position but it would not prevent side swinging of the device and very often it is desirable to couple the cars while moving and the rocking of the cars would tend to cause the 95 couplers to swing sideways and hence out of alinement, and to avoid this condition I utilize the spring 11 for maintaining the device together with the coupler head in a normal central position. 100

This result is brought about by having the face of the yoke 12 which is adjacent the housing 4 to bear against the lower edge of the housing 4 and maintained in such contact by the pressure of the spring 11. 105 If now the yoke 12 is moved to the right, the inner edge of the housing 4 contacting with the yoke 12 as indicated by the numeral 20 in Fig. 2 will act as a pivotal point about which the yoke 12 and the housing 4 will pivot and the tension on the spring 11 will be increased with the result that if the yoke 12 is not maintained in the position just referred to by some external force, that the spring will cause the 110 yoke 12 to move back to normal position with the line A¹—A¹ coinciding with the true center line A—A.

My invention will also permit of the draw head or coupler swinging laterally and moving downwardly simultaneously as would be the case if two coupled cars were passing over a break of grade on a curve. 120

While I have described the preferred embodiment of this invention, it is evident 125 that others may make various changes in the construction, combination and arrangement of the several parts without departing from the spirit and scope of the invention as defined in the appended claims. 130

What I claim is:—

1. A draw-bar carrier adapted for attachment to a car body and to allow vertical and horizontal movement of the draw-bar relative to the car body, comprising a pair of securing means attached to the car body, a yoke member to receive the bar and provided with means to maintain the draw-bar in a predetermined position on the yoke, a hollow member pivotally secured to each securing means and, depending therefrom, a supporting member pivotally secured to each end of the yoke member and each extending into one of the hollow members, and a spring positioned within each hollow member and interposed between the hollow member and the supporting member.
2. A draw-bar carrier for suspension from a car body comprising a yoke member, a pair of securing means attached to the car body, a hollow member pivotally secured to each securing means, a supporting member pivotally secured to each end of the yoke member and extending into the corresponding hollow member, and a spring positioned within each hollow member and interposed between the hollow member and the supporting member to allow the yoke member to yield relatively to the car body.
3. A draw-bar carrier adapted for attachment to a car body and to allow a vertical and a horizontal movement of the draw-bar relative to the car body comprising a pair of securing means attached to the car body, a yoke member to receive the draw-bar, a hollow member pivotally secured to each securing means to swing in a lateral direction only relative to the car body, a supporting member pivotally secured to each end of the yoke member to swing in a lateral direction only relative to the yoke member and extending each into one of the hollow members, and a spring positioned within each hollow member and interposed between the hollow member and the supporting member.
4. A draw-bar carrier comprising in combination securing means suspended from the car body, a yoke member to support the draw-bar, and a centering device provided with a surface engaging the surface of the yoke member, said co-acting surfaces resting in the same common plane, and also pivotally attached to the securing means to permit the yoke member to move laterally of the car body, the centering device also having a yielding member connected to the yoke whereby the yoke member is returned to normal position when moved therefrom.
5. A draw-bar carrier comprising in combination securing means suspended from the car body, a yoke member to support the draw-bar, a centering device provided with a flat surface at one end engaging a like surface on the yoke member and having a pivotal connection at the other end for suspending the centering device from the securing means, and a connecting member for securing the yoke and centering device together and a spring interposed between the centering device and the connecting member.
6. A draw-bar carrier for suspension from a car body comprising supporting means attached to the car body, supporting means for a draw-bar mounted to swing laterally and move vertically under stress, a yielding connecting member interposed between and pivotally attached to the supporting means on the car body and for the draw-bar and provided with a flat surface engaging a like surface on one of the supporting means, said engaging surfaces resting in the same common plane when the parts are in normal position but being moved out of the common plane when the supporting means for the draw-bar is moved laterally.

In testimony whereof I affix my signature.
ERNST LARSSON.
